CLAIM

The ornamental design for a wall-mount holder, as shown and described.

DESCRIPTION

FIG. 1 is a perspective view of a first embodiment of a wall-mount holder showing our new design as embodied in a letter holder;

FIG. 2 is a top plan view thereof;

FIG. 3 is a front elevational view thereof;

FIG. 4 is a bottom plan view thereof;

FIG. 5 is a right side elevational view thereof, the left side elevational view being a mirror image;

FIG. 6 is a rear elevational view thereof;

FIG. 7 is a perspective view of a second embodiment thereof, showing our new design as embodied in a three-tier wall-mount spice rack;

FIG. 8 is a top plan view thereof

FIG. 9 is a front elevational view thereof;

FIG. 10 is a bottom plan view;

FIG. 11 is a right side elevational view thereof, the left side elevational view being a mirror image; and,

FIG. 12 is a rear elevational view thereof.

The broken-line disclosure in the views is understood to illustrate unclaimed portions of the article in which the claimed design is embodied, but which form no part of the claimed design.
